UNITED STATES PATENT OFFICE.

EMORY J. LIPPS AND LLOYD H. LIPPS, OF FOUNTAIN HILL BOROUGH, LEHIGH COUNTY, PENNSYLVANIA, ASSIGNORS OF FIFTY-ONE ONE-HUNDREDTHS TO SAID EMORY J. LIPPS AND FORTY-NINE ONE-HUNDREDTHS TO SAID LLOYD H. LIPPS.

METHOD OF UNITING TEXTILE STRANDS.

1,206,556.

Specification of Letters Patent. Patented Nov. 28, 1916.

Application filed March 21, 1916. Serial No. 85,552.

To all whom it may concern:

Be it known that we, EMORY J. LIPPS and LLOYD H. LIPPS, citizens of the United States, residing at Fountain Hill borough, 5 in the county of Lehigh and State of Pennsylvania, have invented certain new and useful Improvements in Methods of Uniting Textile Strands, of which the following is a specification.

10 In doubling and twisting threads and the like, after each thread has been subjected to what is known as a "first-time" twist and wound on its individual bobbin, the two threads are transferred to a common bobbin. 15 They are then subjected to a "second time" twist, accomplished by rotating the latter bobbin on its own axis as the threads are drawn therefrom substantially longitudinally of said axis. Since the threads as de- 20 posited on the second bobbin are not in any way united with each other, as by being twisted about each other, but lie simply side by side, it is necessary in the "second time" operation to employ a flier or equivalent to 25 keep them together; because of the abrasive action of this device on the threads the draft speed in the "second time" operation is necessarily limited, and at the best the operation is attended with frequent breakage of 30 the threads, involving annoying and time-wasting interruptions. To overcome this it has been proposed to introduce a preliminary twisting operation before the threads are subjected to the "second time" twist, 35 such preliminary twisting operation involving a twist of relatively long pitch designed simply to hold the two threads united or together, and thus make unnecessary the use of a flier or the like-abrading medium, dur- 40 ing the "second-time" twisting operation. The means for accomplishing this so-called "preliminary second-time twist" is complicated and of a character requiring special skill to control it and preserve it in proper 45 working order, and its use obviously involves an operation performed wholly apart from any other operation on the material.

The object of this invention is to make the use of fliers unnecessary and in a simple way, 50 by a treatment performed simultaneously with the doubling operation, to connect the threads with each other so that they will be adapted to undergo the second-time twisting or spinning operation, *i. e.*, in their doubled

state be bound together, as in this second-time operation they are drawn from the rotating wound package into which they have been formed. This we have in practice accomplished by causing the wrapping of one (or each) of the strands around the other alternately right and left by drawing the strands lengthwise over a suitable surface and simultaneously effecting back and forth movement as between said surface and the strands crosswise of the line of draft and forming the strands, thus consequently and while so bound together, into a wound package.

It is not indispensable that the right and left wrapping take place simultaneously with the doubling, as the doubling may in some instance have been already performed. Nor is it indispensable that the wrapping be effected by drawing the threads over a surface as between which and the strands back and forth movement crosswise of the line of draft is caused. Nor is it indispensable, so far as is concerned the idea of wrapping by drawing the strands over a surface as between which and the strands the said back and forth movement is effected, that the wrapped strands be formed into a wound package. Nor is it indispensable, though it will usually be the case, that the strands be drawn lengthwise while the wrapping is proceeding, the broad idea in this aspect of our invention being the right and left wrapping of one strand around the other and forming the strands, as bound together by the wrapping, into a wound package.

In the annexed drawings, Figure 1 is a fragmentary front elevation of one form of a machine suitable for performing the invention; Fig. 2 is a vertical sectional view of what is shown in Fig. 1; Fig. 3 is a plan view, showing parts not appearing in Fig. 1; and, Fig. 4 is a view illustrating diagrammatically the alternate right and left wrapping of either strand around the other.

a is the frame of the machine, being a doubling machine of well-known type; *b* the rail on which is supported the pair of spools *c* on which the strands with the first time twist are wound; *d* is the spool on which is wound the material formed in accordance with this invention, the same being suitably journaled in the frame; *e* is a

traverse rail having a guide *f* and arranged to reciprocate in the frame transversely of the line of draft of the material; *g* is a wheel for rotating the spool *d*, the same being arranged on a shaft *h* journaled in the frame; and *i* the mechanism for rotating the shaft *h* and reciprocating the traverse rail. At *j* and *k* are shown any suitable means for controlling the tension of the material and automatically stopping the rotation of the spool *d* on breakage of the thread or the like, the same not requiring to be described herein.

Suitably supported more or less near the spool *d* in brackets *l* projecting from the frame of the machine is a bar *m* which is preferably cylindrical in cross section and is arranged to reciprocate in said brackets. The said bar in the present adaptation is reciprocated from the traverse rail through the medium of pinions *n* and *o* which rotate as one and may be journaled on a bracket *p* projecting from the frame, respectively meshing with rack teeth *n'* and *o'* formed on the traverse rail and bar *m*. The strands extend over the bar *m* and traverse rail to the spool *d*. The bar *m*, as it reciprocates, preferably presents a longitudinally smooth surface to the strands. The throw of the bar *m* is somewhat greater than that of the traverse rail.

q is a special guide for the strands projecting from rail *e* below bar *m*, being set preferably obliquely in the present instance (but it may be otherwise formed or adapted) to keep the strands close together and preferably in actual contact with each other and thus insure their wrapping around each other, as they will not do if separated at this point.

In the operation of the mechanism specifically shown, the means *i* while causing the spool *d* to rotate also causes the traverse rail and bar *m* to reciprocate in opposite directions, thus, while the traverse rail lays the doubled material on the spool *d* in coils progressing back and forth from one to the other end of the spool, the coaction of said traverse rail and bar *m*, because one moves relatively (in this case, oppositely) to the other, results in each strand being rolled and thus wrapped around the other in coils progressing alternately to right and left as diagrammatically shown in Fig. 4. This figure is intended to illustrate simply the reverse, or alternately right and left, wrapping of the coils, only one of the strands being here shown as affected by the wrapping action; and while we do not wish to exclude such a wrapping of coils as would

affect but one of the strands, still in actual practice it will usually be found that each of the strands will receive a wrapping action around the other.

In the present instance, as fast as the 65 wrapping proceeds the wrapped portion of the strands is wound up in a package on the spool *d* so that the wrapped condition is retained in the material as an incident to its being wound, more or less tightly, on said spool, and further remains therein for the purpose and with the effect in actual practice of keeping the strands bound together as in the spinning operation the material is drawn from the spool *d* onto a receiving 70 75 spool or bobbin.

Having thus fully described our invention, what we claim as new and desire to secure by Letters Patent is:—

1. The herein-described method of uniting textile strands which consists in drawing the strands lengthwise and simultaneously wrapping one strand around the other alternately right and left and forming the strands as thus wrapped into a wound 80 85 package.

2. The herein-described method of uniting textile strands which consists in drawing the strands lengthwise over a suitable surface and simultaneously effecting relative 90 back and forth movement as between said surface and the strands crosswise of the line of draft, whereby to wrap one strand around the other alternately right and left.

3. The herein-described method of uniting 95 textile strands which consists in wrapping one strand alternately right and left around the other and forming the strands as thus wrapped into a wound package.

4. The herein-described method of uniting 100 textile strands which consists in drawing the strands lengthwise over a suitable surface and simultaneously effecting relative movement as between said surface and the strands crosswise of the line of draft, whereby to wrap one strand around the other, and forming the strands as thus wrapped into 105 a wound package.

5. The herein-described method of uniting 110 textile strands which consists in drawing the strands lengthwise and simultaneously moving one strand around the other alternately right and left repeatedly, whereby to cause the first strand to be laid around the other in a repetition of alternately right and left 115 wrappings.

In testimony whereof we affix our signatures.

EMORY J. LIPPS.
LLOYD H. LIPPS.
